MANUFACTURE OF MOTOR FUEL

Le Roy G. Story, White Plains, N. Y., assignor to
 The Texas Company, New York, N. Y., a corporation of Delaware

Application May 27, 1939, Serial No. 276,149

4 Claims. (Cl. 196—10)

This invention relates to the manufacture of motor fuel and has to do particularly with the production of high antiknock gasoline hydrocarbons by the alkylation of low boiling isoparaffins with olefins.

In accordance with the invention, paraffin hydrocarbons, suitably those containing between 2 and 5 carbon atoms, are dehydrogenated to produce olefins and the hot dehydrogenation products contacted with cool liquid products from an alkylation process, thereby vaporizing the alkylation products to form a vapor fraction containing gasoline and normally gaseous hydrocarbons. The vapor fraction is separated into an alkylate and normally gaseous hydrocarbons, which are fractionated to produce a fraction rich in normal butanes which is returned to the dehydrogenation operation, and a fraction rich in olefins which is charged to the alkylation operation.

The invention will be more fully understood from the following description read in connection with the accompanying drawing which shows one form of apparatus suitable for carrying out the process of the invention.

Referring to the drawing, a paraffin charging stock, such as propane or butane, or a mixture thereof, is charged through the line 1 to a heating coil 3 located in a heater 4. In the heating coil the hydrocarbons are raised to a temperature sufficiently high whereby substantial dehydrogenation of the hydrocarbons takes place when contacted with a dehydrogenation catalyst. Such a temperature will usually range between about 400° and 700° C. The hot products are transferred from the coil 3 through the line 5 to a catalyst chamber 6 containing a dehydrogenation catalyst, such as activated alumina, chromium oxide or chromium oxide on alumina. In passing through the catalyst chamber, the hot products are intimately contacted with the catalyst and the hydrogen split therefrom. About 30 to 50% of paraffins may be converted into olefins when passing through the catalyst under the above conditions. The dehydrogenation products are transferred from the catalyst chamber 6 through the line 7 to a vaporizer 8 wherein the hot dehydrogenation products are contacted with cool alkylation products introduced through the line 10. In the vaporizer the alkylate is substantially vaporized and the hot dehydrogenation products cooled. The products of higher boiling point than gasoline are separated as a liquid fraction in the vaporizer and may be withdrawn from the bottom thereof through the line 12. A vaporous fraction containing gasoline and lighter hydrocarbons, is passed overhead from the vaporizer through vapor line 14 and condenser 15 to an accumulator 16. Uncondensable or permanent gases, such as hydrogen, methane, and all or a portion of the ethane and the ethylene, may be released from

the accumulator through the gas release line 17. The liquid fraction comprising an unstable alkylation gasoline is passed from the accumulator through the line 18 and pump 19 to stabilizer 20. A stabilized gasoline is separated in the stabilizer and withdrawn from the bottom thereof through line 22. A vapor fraction containing all or a portion of the normal butane and lighter hydrocarbons, is passed overhead from the stabilizer through the line 23 to a fractionator 24. In the fractionator 24 a paraffin fraction, comprising normal butane, is separated as a condensate and passed from the lower portion of the fractionator through the line 25 by the pump 26 to the heating coil 3. A gaseous fraction rich in olefins is passed overhead from the fractionator through the line 28 and condenser 29 and charged through the line 30 by a pump 31 into the line 32, of an alkylation system. In the line 32 a mixture including catalyst and isobutane is circulated by the pump 33 through a mixer 34, cooler 35 and reaction chamber 36. The reaction products from the reactor 36 are passed through a line 37, any portion or all being recirculated through the line 38 where it is picked up by the pump 33. A portion of the products withdrawn from the reactor 36 through the line 37 and not recycled, is passed to a separator 40 wherein the catalyst separates from the hydrocarbon and may be withdrawn through the line 41 and discharged from the system or recycled through the line 42. Fresh catalyst to make up for that discharged through the line 41 may be added through the line 43. Extraneous isobutane may be introduced into the alkylation system through the line 49. The hydrocarbons separated out in the separator 40 are passed through the line 44 to a neutralizer 45 wherein the hydrocarbons are contacted with a neutralizing agent such as dilute caustic soda introduced through the line 46 and discharged through the line 47. The neutralized hydrocarbons are passed through the line 48, pump 50 and line 10 to the vaporizer 8, referred to hereinafore.

In the alkylation operation, a suitable catalyst such as aluminum chloride, hydrated boron trifluoride or sulfuric acid, may be used. Sulfuric acid of about 90 to 100% concentration is preferable. The catalyst is intimately contacted with the hydrocarbons in the liquid phase at a temperature of about zero to 100° F. and preferably about 60° to 90° F. An excess of isobutane over the olefins is maintained in the charging stocks and a higher ratio of isobutane to olefins is maintained in the reaction mixture.

If the charge to the alkylation system contains a substantial amount of C₃ hydrocarbons, such as propane and propylene, it may be desirable to separate from the hydrocarbons, discharged from the neutralizer 45, the propane.

For this purpose it is contemplated that a fractionator or other means of separating the propane may be installed in the line 48.

As an example of the operation of the invention, normal butane is heated to a temperature of about 550° C. and contacted with a dehydrogenation catalyst comprising chromium oxide deposited on activated alumina. About 50% of the normal butane is converted into butylenes. The hot dehydrogenation products are passed to a vaporizer wherein they are intimately contacted with cool liquid products from a cooperating alkylation system. Substantially all the alkylate of gasoline boiling point and lighter is vaporized and a fraction higher boiling than gasoline is separated as a liquid. The vapors are cooled to form an unstable alkylate containing normally gaseous hydrocarbons, including the C₄'s and a portion of the C₃ hydrocarbons. The lighter hydrocarbons including hydrogen, methane, C₂ hydrocarbons and a portion of the C₃ hydrocarbons, are discharged from the system. The unstabilized alkylate is subjected to stabilization to separate overhead substantially all the normally gaseous hydrocarbons. A stabilized alkylate of gasoline boiling range is withdrawn from the system. The normally gaseous hydrocarbons separate overhead from the stabilizer are fractionated to separate normal butane which is returned to the dehydrogenation operation. The remaining gases predominating in butylene and isobutane are charged along with additional extraneous isobutane if necessary to produce an excess of isobutane over olefins, to an alkylation operation wherein the isobutane is alkylated by the olefins in the presence of sulfuric acid of about 98% concentration at a temperature of about 60° F. The alkylation products are separated from the catalyst, neutralized and charged to the vaporizer to which the hot products from the dehydrogenation operation are introduced. A gasoline alkylate is recovered from the system, having an octane number of about 90.

The present invention has the advantage of utilizing the heat from the dehydrogenation operation for redistilling the alkylate. The alkylate also scrubs and removes any tarry materials from the hot dehydrogenation products. A further advantage of the invention is the elimination of fractionation of the alkylate and dehydrogenation products which are expensive operations when the processes are conducted separate.

Obviously many modifications and variations of the invention as hereinbefore set forth, may be made without departing from the spirit and scope thereof, and therefore only such limitations should be imposed as are indicated in the appended claims.

I claim:

1. A process for the manufacture of high anti-knock gasoline hydrocarbons, which comprises dehydrogenating normally gaseous hydrocarbons predominating in paraffins containing between 2 and 5 carbon atoms to form a hot mixture of paraffins and olefins, contacting said hot mixture with liquid products from an alkylation operation, thereby vaporizing said liquids to form a vaporous and gaseous mixture of dehydrogenation and alkylation products, fractionating said vaporous mixture to form an alkylate and a normally gaseous hydrocarbon fraction containing olefins and paraffins, fractionating said gaseous fraction to produce a fraction rich in olefins and a fraction rich in paraffins, charging said

olefin-rich fraction to the alkylation operation wherein said olefins are alkylated with isobutane in the presence of an alkylation catalyst and returning said paraffin-rich fraction to the dehydrogenation operation.

2. A process for the manufacture of high anti-knock gasoline hydrocarbons, which comprises dehydrogenating normally gaseous hydrocarbons predominating in paraffins containing between 2 and 5 carbon atoms to form a hot mixture of paraffins and olefins, contacting said hot mixture with liquid products from an alkylation operation, thereby vaporizing said liquids to form a vaporous and gaseous mixture of dehydrogenation and alkylation products, separating from said mixture an unstabilized alkylate, stabilizing the alkylate to form a stable alkylate and a normally gaseous hydrocarbon fraction predominating in olefins and paraffins containing between 2 and 5 carbon atoms, fractionating said fraction to separate a fraction rich in olefins and a fraction rich in paraffins, returning said paraffin-rich fraction to the dehydrogenation operation, subjecting said olefin-rich fraction to an alkylation operation in the presence of excess isobutane and an alkylation catalyst whereby the isobutane is alkylated by the olefins, separating the alkylation products from the catalyst and passing said products to the operation in which the alkylation products are contacted with hot products of dehydrogenation.

3. A process for the manufacture of high anti-knock gasoline hydrocarbons, which comprises dehydrogenating n-butane to butylene, contacting the hot dehydrogenation products with cool products from an alkylation operation, thereby vaporizing the alkylation products to form a vaporous fraction, separating from said fraction an unstabilized alkylate containing gasoline, normal butane and butylenes, stabilizing said alkylate to produce a stable alkylate and a stabilizer overhead containing said normal butane and butylenes, fractionating the stabilizer overhead to form a fraction rich in butylenes and a fraction rich in normal butane, returning said n-butane fraction to the dehydrogenation operation, charging said butylene fraction to an alkylation operation wherein isobutane is alkylated by the butylenes in the presence of an alkylation catalyst, recovering from the alkylation operation an alkylate and passing said alkylate to the operation in which the hot dehydrogenation products are contacted with cool alkylation products.

4. A process for the manufacture of high anti-knock gasoline hydrocarbons, which comprises subjecting low boiling paraffin hydrocarbons to dehydrogenation, thereby forming a hot mixture of dehydrogenation products, contacting said hot dehydrogenation products with cooler products from an alkylation operation thereby forming a vapor mixture, separating from said mixture a normally liquid fraction, also separating from said mixture a light fraction containing normally gaseous olefins, subjecting said light fraction to an alkylation operation in the presence of an alkylation catalyst and low boiling isoparaffins in excess of the olefins, separating a hydrocarbon fraction containing alkylate from the reaction products and passing said hydrocarbon fraction to the operation in which the products of the alkylation operation are contacted with the hot dehydrogenation products.
